UNITED STATES PATENT OFFICE.

JULIAN KENNEDY, OF PITTSBURG, PENNSYLVANIA.

HOT-BLAST STOVE.

SPECIFICATION forming part of Letters Patent No. 728,185, dated May 12, 1903.

Application filed March 10, 1903. Serial No. 147,107. (No model.)

To all whom it may concern:

Be it known that I, JULIAN KENNEDY, of Pittsburgh, Allegheny county, Pennsylvania, have invented a new and useful Hot-Blast Stove, of which the following is a full, clear, and exact description, reference being had to the accompanying drawings, forming part of this specification, in which—

Figure 1 is a vertical section of my improved stove with the central part broken away. Fig. 2 is a partial vertical section on the line II II of Fig. 1. Fig. 3 is a horizontal cross-section on the line III III of Fig. 2; and Figs. 4, 5, and 6 are partial horizontal sections on the lines IV IV, V V, and VI VI, respectively, of Fig. 1, showing the arrangement of the checker-work.

My invention relates to the class of hot-blast stoves, and is designed to improve the distribution of the gases and make the temperature uniform in its different portions. It is also designed to provide an improved arrangement of the chimney-valve and cold-blast inlet, whereby the flues may be easily cleaned out, and also to provide a cheap, simple, and efficient construction.

In the drawings I show a two-pass stove with the outer annular wall 2 and the inner concentric wall 3, which is preferably a double wall, as shown, and which incloses the combustion-chamber 4. The brick foundation 5 is provided with an annular flue 6, which extends around a transverse arch 7, the flue 8 extending under the arch and connecting its opposite portions. The chimney-outlet 9 and the cold-blast inlet 10 are located on opposite sides in register with the ends of the cross-flue 8. By thus locating these flues opposite to each other a blast can be driven through to clean out the dust and accumulation which settles to the bottom of the stove. Into this flue also open three cleaning-ports 11, 12, and 13, closed by suitable doors 14, and an air-relief flue 15 also opens into the flue 6, these flues being shown in Fig. 2.

A hot-blast port 16 leads into the lower end of the combustion-chamber and over the flue 6, it preferably being arranged at an upward incline, as shown, and having the usual hot-blast valve 17. The gas-burner port 18 is opposite to the hot-blast port at the lower end

of the combustion-chamber and is arranged at an opposite incline thereto.

The flue 6 is open upwardly to the checker-work in the annular space around the combustion-chamber except where it is covered by the flues 16 and 18.

The checker-work is arranged in radial interlocked form, 19 being the radial bricks, and 20 the bricks arranged in concentric circular rows between and interlocking with them. The bricks 20 at one level abut against the radial bricks, which are continuous, as shown in Fig. 6, while at the next level the bricks 20 are continuous and the radial bricks 19 abut against them and cover the joints, as shown in Fig. 5. This checker-work formation is supported on radial arches 21, (shown in Figs. 1 and 4,) these arches being supported upon ledges at the lower portions of the outer wall 2 and the outer portion of the inner wall 3.

In the operation of the stove when it is being heated the products of combustion from the gas-burner rise through the combustion-chamber and thence descend through the checker-work into the annular flue 6, whence they pass out through the chimney-flue. When the gas-burner and chimney-flue are closed and the cold-blast inlet and hot-blast outlet are open, the air entering port 10 flows around the flue 6 and through the flue 8, and is thus evenly distributed. This air rises through the checker-work in substantially equal amounts in the different parts and then passes down through the central flue and out through the hot-blast valve.

The advantages of my invention result from the even distribution of the gases while heating and the air passing in the opposite direction, resulting from the peculiar arrangement of the flues in connection with the radial checker-work. The oppositely-located chimney-port and cold-blast inlet provide for a simple and effective cleaning of the stove.

The invention may be applied to a three or four pass stove, and many other variations may be made in the form and arrangement of the parts without departing from my invention.

I claim—

1. A hot-blast stove having a lower annular flue with a central arch containing a cross-

flue connecting the opposite sides of the annular flue, a central combustion - chamber with its lower end over the arch, a gaseous inlet and hot-blast outlet leading into the lower end of the combustion-chamber, radial checker-work around the combustion-chamber and opening downwardly into the annular flue, said flue having a chimney-outlet and a cold-blast inlet leading into it; substantially as described.

2. A hot-blast stove having an annular flue in its base with a cross-flue connecting its opposite sides, and oppositely-located chimney and cold-blast ports opposite to the ends of the cross-flue; substantially as described.

3. A hot-blast stove having a lower central

arch with a cross-flue extending under it and opening into an annular flue, a central combustion-chamber above the arch, annular checker-work surrounding the combustion-chamber and opening downwardly into the annular flue, and a chimney-port and cold-blast port opening into the annular flue on opposite sides substantially in registry with the ends of the cross-flue under the arch; substantially as described.

In testimony whereof I have hereunto set my hand.

JULIAN KENNEDY.
